J. D. BRADY

TRAVELING VALVE

Filed July 26, 1924

Fig. 1. — Fig. 2.

John D. Brady Inventor

By ~~Amelia~~ ^{John} Allwine
Attorney

UNITED STATES PATENT OFFICE.

JOHN D. BRADY, OF BARTLESVILLE, OKLAHOMA.

TRAVELING VALVE.

Application filed July 26, 1924. Serial No. 728,460.

To all whom it may concern:

Be it known that I, JOHN D. BRADY, a citizen of the United States, residing at Bartlesville, in the county of Washington and State of Oklahoma, have invented certain new and useful Improvements in a Traveling Valve, of which the following is a specification.

This invention relates to improvements in well pumping equipment.

The primary object of this invention is the provision of an improved plunger or piston arrangement for the pumping equipment of wells.

15 A further and important object of this invention is the provision of a traveling valve for well pumping equipment including novel means for maintaining plunger cups and rings on the plunger barrel, and 20 to maintain the valve part in effective working condition.

25 A further object of this invention is the provision of an improved traveling valve and piston construction for the pumping equipment of oil wells and the like, embodying an assemblage of parts which are 30 locked in positive and effective manner, and which cannot become detached, as is sometimes the case with conventional plunger or piston arrangement, very often resulting in loss of parts and plugging of wells.

35 A further object of this invention is the provision of a traveling valve for the pumping equipment of oil wells and the like, embodying a novel nut lock arrangement 40 for maintaining the parts of the traveling valve in assembled relation, so that the same cannot rotate or move with respect to each other, and thus preventing possibility of 45 detachment of parts incident to rotation of the valve in the working barrel.

Other objects and advantages of this invention will be apparent during the course of the following detailed description.

45 In the accompanying drawing, forming a part of the specification, and wherein similar reference characters designate corresponding parts throughout the several views.

50 Figure 1 is a side elevation showing the assembled details of the improved traveling valve or piston arrangement.

Fig. 2 is a cross sectional view taken longitudinally through the assembled details 55 of the improved traveling valve,

Fig. 3 is a cross sectional view taken substantially on the line 3—3 of Figure 2.

Fig. 4 is a fragmentary cross sectional view taken through the traveling valve details substantially on the line 4—4 of Figure 2.

Fig. 5 is a plan view of a novel type of follower used with the traveling valve, and

Fig. 6 is a perspective view showing a novel type of locking key used for retaining 65 the parts of the traveling valve against relative movement.

In the drawing, wherein for the purpose of illustration is shown only a preferred embodiment of the improved valve, the letter A may generally designate the improved traveling valve, piston, or plunger, which may include the barrel B; cup arrangement C; follower D; nut E; crown F; and key G for connecting the parts of the traveling 70 valve against relative movement when in assembled relation.

Referring to the barrel B, the same includes a cylindrical shaped body portion 10, providing an internal passageway 11 there-through, with an externally smooth surface 12. At the lower end of the body portion 10 a circumferentially enlarged bottom head 14, is formed and provides a shoulder 15 at the juncture of the body portion 10 with the bottom head 14, extending annularly about the external surface 12. This bottom head 14 is of the usual construction, and is integral with the body portion 10, having lateral openings 16 therein communicating with the passageway 11 through the barrel B. At its upper end the barrel B is provided with an integral reduced portion 18, which is externally screw threaded. Longitudinally extending diametrically opposed slots 95 or grooves 20 are provided inwardly of the external surface 12 of the body 10, at its upper end, having an outlet at their upper ends on the shoulder 21 at the juncture of the body portion 10 with the reduced portion 18.

The cup arrangement C includes the conventional fiber or flexible cups 25, with the metal spacing rings or sleeves 26 therebetween; said cups and rings being slipped over the body portion 10, from the reduced upper end of the barrel B, so that they are held from slipping off the lower or bottom end of the barrel B because of the fact that the lowermost cup 25 engages against the 110

annular shoulder 15 of the bottom head 14. These cups and rings are freely slideable along the body portion 10 of the barrel, to permit their easy attachment and removal 5 from said body portion, prior to the clamping of the same in their fixed relation thereon.

The follower D is preferably of ring shaped formation, somewhat similar in appearance to one of the spacing rings 26, and it includes the reduced lower portion 28 adapted to fit in the uppermost cup 25 in the same manner as one of the spacing rings 26. The upper enlarged portion 29 10 of the follower is preferably provided with the substantially diametrically opposed notches 30 inwardly of the top edge 31 thereof, and a portion of this top edge 31 provides an internal beveled seat 33 against 15 which the nut E may engage, as will be subsequently described. As an important feature of the follower D, the same is provided with diametrically disposed pins 35, fixed in any approved manner in the follower portion 29, so that the inner end portions 36 thereof extend inwardly of the inside periphery of the passageway 38 through the follower D, and so that these ends 36 will 20 slidably engage in the slots or grooves 20 of the barrel B, when the follower D is slipped into position over the barrel. In this manner the follower may move longitudinally of the barrel, but is prevented from rotational movement thereon, and the importance of which feature will subsequently 25 appear.

The nut E is preferably internally screw threaded, as at 40, for adjustment over the reduced externally screw threaded end 18 of the barrel B, and the lower beveled edge 41 thereof is adapted to engage against the beveled edge 33 of the follower D to clamp the latter down upon the cup and ring arrangement B to hold the same fixed on the 30 valve barrel. This nut E provides an external polygonal wrench engaging structure, preferably hexagonal, and circumferentially of this hexagonal wrench engaging structure a groove 42 is provided, intersected by 35 vertical slots 43 through each of the side faces of the nut. Integral with and considered as a part of the nut E is the upstanding reduced portion 46, externally screw threaded at 47, for detachable connection of the crown F thereon. This portion 46 provides a passageway 48 therethrough, upwardly of the screw threaded 40 passageway 40 and aligning therewith.

The crown F includes the substantially 45 cylindrical shaped body 50, provided with the longitudinal slots 51 therethrough, extending to the passageway 53 through the crown, and the lower internal screw threads 54 are provided for detachable threading 50 over the screw threads 47 of the nut E.

When the crown F is screw threaded upon the nut E the same provides a valve cage within which the check ball K may reciprocate; the check ball K normally seating in the upper edge 55 of the nut portion 46, in 55 order to close the passageway through the barrel B from communication with the working barrel (not shown) above the ball K. Of course, the crown or valve cage F provides a top wall 58 upon which an upwardly extending reduced externally screw threaded shank 59 is provided for receiving any suitable coupling, by means of which the cable or pumping string may be connected to the traveling valve A.

Referring to the locking key G, the same preferably includes a vertical, preferably straight portion 60, midway between the ends of which, and laterally of each side thereof, the segmental tongues or fingers 61 and 62 extend in a concentric arrangement. The tongues 61 and 62 together provide a segment greater than 180°. In position the tongues 61 and 62 are slipped in the nut groove 42, and snapped past the greatest diameter of the nut in this groove 42, so that the resiliency of the tongues or fingers 61 and 62 maintain the key G in position on the nut. The upper and lower locking fingers 63 and 64 of the part 60 of the key G extend through a vertical groove 43 in the nut E in which they are positioned, and the tip ends of these fingers 63 and 64 respectively extend above and below the edges of the nut polygonal body for reception within recesses 65 and 30; the former recesses 65 being provided upwardly of the lower edge 66 of the valve crown F.

The assemblage of parts will be apparent from the foregoing description. The follower D is, of course, prevented from rotational movement upon the body of the barrel B, and when the nut E has been clamped upon the barrel to fix the follower D and the cup and ring arrangement in a fixed relation, the crown F may be adjusted on the upper externally screw threaded portion 46 of the nut E until the desired recess 65 aligns with the desired recess 30 in the upper edge of the follower D. Then by merely slipping the key G in the relation described and shown in the drawings, upon the polygonal portion of the nut E, the same will lock the crown F to the follower D and to the nut E, and will absolutely lock the barrel; follower; nut; and crown or valve cage F in a relation which cannot be accidentally altered. The fact that the tongues 61 and 62 are resilient and engage the nut in the groove 42 thereof for the major circumference of said groove insures that the key cannot slip out of the relation in which it is shown in Figures 1 and 3 of the drawing, and the parts of the valve will always be keyed in a definite relation until they

are manually altered. The provision of the vertical grooves 43 to the polygonal body of the nut E insures that a close adjustment may be had, by means of which these grooves 5 43 may be aligned with the recesses 30 and 65 of the valve follower 30 and cage F, respectively.

From the foregoing description of this invention it is apparent that a novel type 10 of traveling valve or piston arrangement for pump equipment has been provided, in which there will be no accidental detachment of parts during pumping operations, such as are sometimes occasioned with conventional pump plungers.

Various changes in the shape, size, and arrangement of parts may be made to the form of invention herein shown and described, without departing from the spirit 20 of this invention or the scope of the claims.

I claim:

1. In a pump plunger a barrel, cup and rings on the barrel, a nut on the barrel for clamping the cup and rings in position 25 thereon, a crown detachably carried by the nut, and means for locking the barrel and crown and nut against relative movement in any direction.

2. In a pump plunger a barrel providing 30 an integral annular outwardly extending shoulder on the lower portion thereof, cups and rings adapted to be slipped from the upper portion of the barrel to engage said annular shoulder, a nut on the barrel for 35 clamping the cups and rings in position thereon against said annular shoulder, a crown on the nut, and means for locking the barrel and crown against relative movement in any direction.

3. In a device of the class described a barrel, cups and rings in the barrel, means 40 to hold the cups and rings on the barrel at one end thereof, a follower slideable on the opposite end of the barrel and held thereon against rotation about the barrel, and a nut adjustable on said last mentioned end of the barrel to engage against the follower for clamping the cups and rings in a fixed relation on the barrel.

4. In a device of the class described a barrel, cups and rings on the barrel, means 45 to hold the cups and rings on the barrel at one end thereof, a follower slideable on the opposite end of the barrel and held thereon against rotation about the barrel, a nut adjustable on said last mentioned end of the barrel to engage against the follower for clamping the cups and rings in a fixed relation on the barrel, a crown on the nut, and means to lock the crown in fixed relation to the follower.

5. In a device of the class described a barrel, cups and rings on the barrel, means 50 to hold the cups and rings on the lower end of the barrel, a follower slideable on

the upper end of the barrel and held thereon against rotation about the barrel by means of pins fixed with the follower slidably extending into longitudinal slots provided in the barrel, and a nut adjustable on the upper end of the barrel adapted to engage against said follower to clamp the same and the cups and rings in a fixed relation on the barrel. 70

6. In a traveling valve a barrel providing 75 a passageway therethrough, cups and rings exteriorly positioned on the barrel and held against movement off the lower end thereof, a follower on the upper portion of the barrel, means permitting longitudinal movement of the follower on the barrel and holding the same against rotational movement thereon, a nut adjustable on the upper end of the barrel adapted to be clamped against 80 said follower, a valve cage adjustably connected with said nut, a valve member in the valve cage adapted to seat against the upper end of said nut to close off communication of the passageway through said barrel, and means for locking the nut, the follower, and the cage against movement in any direction with respect to each other. 85

7. In a traveling valve a barrel, cups and rings on the barrel, a follower connected to the barrel for longitudinal movement 95 thereon and held against rotational movement thereon, nut means for clamping the follower onto the cups and rings, a valve member seating on said nut, a valve cage connected to the nut for receiving said valve 100 member therein, and a key member adapted to be connected to said follower, nut, and valve cage to hold the same in position on the barrel against relative movement with respect to each other. 105

8. In a traveling valve a barrel, cups and rings for the barrel, a follower, means connecting the follower on the barrel to prevent rotational movement thereabout, a nut adjustably connected to the barrel for 110 clamping against said follower, a crown detachably connected to said nut above said follower, and a member adapted to be fixed with said nut and to engage the follower and crown in a locked relation to prevent relative movement of the parts of the traveling valve. 115

9. In a device of the class described a barrel providing a lower annular outwardly extending shoulder and an upper reduced screw threaded end and being provided with slots longitudinally therein from the outer surface thereof below said screw threaded end, cups and rings adapted to be slipped on the barrel to rest against the annular shoulder thereof, a follower adapted to be slipped on the barrel including a passageway therethrough and having an interiorly extending projection adapted to be slipped in said slots of the barrel to hold the fol- 120 125 130

lower in position on the barrel against relative rotation, a nut adapted to be adjusted on the screw threaded end of said barrel to clamp the follower in position against said cups and rings, a crown detachably carried by the nut, said follower and crown having facing recesses therein, and a key member adapted to be fixed with the nut and having projections adapted to extend 10 into the recesses of said follower and crown to hold the nut, the follower, the barrel and the crown against relative movement.

10. In a device of the class described a barrel, cups and rings for the barrel, a follower for the barrel, means connecting the follower to the barrel to permit sliding thereon longitudinally and preventing its movement thereabout, nut means adjustable on the barrel for clamping against said follower to force the latter against said cups and rings, a valve member cooperable with a passageway provided through said nut, a valve cage detachable on said nut for receiving said valve member therein, said nut 20 including a polygonal portion provided with an annular groove therein and having grooves intersecting the annular groove, said follower and crown having recesses extending therein adapted to align with the intersecting grooves of said nut, and a key member including resilient tongues for clamping in the annular groove of the nut and including fingers for extension in the intersecting grooves of said nut and adapted 30 to project into the recesses of the fol-

lower and cage to hold said parts of said device with the exception of the valve member in a fixed non-movable relation.

11. In a locking structure of the class described the combination of a nut providing a polygonal portion having an annular groove inwardly thereof with intersecting grooves through the faces of said nut, and a key member providing resilient gripping tongues adapted to extend into the annular groove for the major portion of the circumference thereof and including upwardly extending fingers adapted to extend through the intersecting grooves of said nut and to extend outwardly of the end surfaces of the 40 45 polygonal portion of said nut.

12. In a device for locking a part on a nut the combination of a nut providing a polygonal body having an annular groove therein intermediate the outer surfaces 50 thereof and said polygonal body having a groove through a side thereof intersecting said annular groove, a part for detachable connection to said nut, and a key including resilient tongues for gripping in the groove 55 through the major circumference thereof and intermediate the ends of said tongues providing a laterally extending projection adapted to extend through the intersecting groove of the nut polygonal body and to engage said part which is detachably connected with the nut to hold the same in non-movable and keyed relation to the nut.

JOHN D. BRADY.
